[57] ABSTRACT

A collapsible tube for toothpaste or the like having its discharge end provided with a nozzle characterized by a cylindrical neck merging into a slightly enlarged tapered head and provided at its inward end with an enlarged collar-like base. This base is united with a grooved portion of the tube's discharge end and the outstanding ledge has cams acting on an internal shoulder carried by a thimble-like sleeve surrounding the base, neck and head. This sleeve is rotatable and slid able. The nozzle is bifurcated to provide a pair of jaw-like furcations whose confronting faces are internally grooved in a manner to provide a dentifrice ejecting passage. The passage is inclined at an oblique angle and the outer end is provided with opposed lips defining an openable and closable mouth. The jaw-like furcations are compressibly squeezable by a rigid encompassing sleeve. This sleeve when oscillated or turned in one direction opens the mouth and when turned in an opposite direction closes the mouth, similar to the action of a chuck.

CLOSURE ASSEMBLY FOR COLLAPSIBLE TUBE

This invention relates to readily openable and closable closures for collapsible tubes such as currently employed as containers for toothpaste, shaving cream, cosmetics and similar ready-to-use commodities and pertains to permanently mounted or captive-type so-called caps and the like and has to do, more particularly, with a longitudinally split expandable and contractable plastic nozzle and a complementary rotary and reciprocatable thimble-like sleeve which encompasses and is maintained in openable and closable position on the nozzle.

An object of the invention is to improve upon captive-type collapsible tube closures and, in so doing, to provide a feasible and acceptable adaptation which well serves the purposes for which the invention has been devised and can be unhesitatingly endorsed by manufacturers, wholesalers, retailers and users.

Briefly the invention is characterized by an integral axially projecting nozzle which embodies a short cylindrical neck merging at its outer end into an integral slightly enlarged head. This neck is provided at its inner end with an outstanding collar-like base which is united with a central axial portion at the dispensing end of the tube and is surrounded by an endless annular relatively shallow channel. The base is provided interiorly with a truncated conical cavity which in turn provides a funnel and communicates with the receptacle portion of the tube or container. The head and neck components of the nozzle are split longitudinally, that is bifurcated in a manner to provide a pair of confronting face-to-face jaw-like furcations. Axial portions of the confronting faces are provided with grooves which conjointly define a passage communicating at one end with the funnel cavity and provided at the tip or outer end of the head with a mouth. More particularly, the portions on opposite sides of the mouth are fashioned into companion lips. The nozzle is made of compressibly resilient plastic material which has the inherent property to expand in a manner to open the mouth. The nozzle when squeezed and compressed closes the mouth and when not compressed causes the mouth to open. The desired opening and closing result is attained with the use of a manually turnable and slidable thimble-like sleeve which surrounds the base, neck and head portions of the nozzle. This sleeve is manually turnable and positionable on the nozzle and is adapted to act on the head in a manner to open and close the mouth at will.

More specifically novelty is predicated on a nozzle which is made of compressibly yieldable plastic material. The sleeve is made of rigid and non-yielding plastic material. The peripheral surface of the head is smooth and annular and this annular surface is inwardly diminished in diameter, bevelled and thus tapered toward the merging outer end of the neck. That portion of the bore of sleeve surrounding the tapered surface is correspondingly bevelled and suitably flared outwardly and snugly encompasses the tapered surface. It follows that when the sleeve is moved and forcibly slid longitudinally and outwardly relative to the head, the head is squeezed and compressed in a manner to force the lips together and thus close the mouth. When the sleeve is slid inwardly toward the base it permits the furcations of the head to expand in a manner to open the mouth.

Then too, novelty is predicated on providing the inner end of the sleeve with a flange which is cooperable with the channel or groove and with an internal shoulder which is cooperable with cams provided on the ledge portion of the aforementioned base part of the nozzle. The diametrically opposite recesses on the thimble-like sleeve facilitate catching hold of and turning the sleeve in a predetermined direction for normally closing the aforementioned mouth and in an opposite direction for opening the mouth when one desires to squeeze dentifrice on the bristles of a toothbrush.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a view in perspective showing a fragmentary end portion of a collapsible toothpaste or similar tube wherein the top or ejecting end of the tube is provided with a captive-type closure assembly constructed in accordance with the invention and showing the lips-equipped mouth closed.

FIG. 2 is a view in perspective similar to FIG. 1 with the sleeve removed and showing the specially contoured split or bifurcated nozzle.

FIG. 3 is a slightly enlarged view primarily in section taken approximately on the plane of the vertical section line 3—3 of FIG. 1 looking in the direction of the indicating arrows.

FIG. 4 is a view in section like FIG. 3 and showing the same construction and arrangement of component parts but with the thimble-like sleeve retracted and with the head of the nozzle expanded and the dispensing mouth of the passage open.

FIG. 5 is a section taken approximately on the plane of the horizontal section line 5—5 of FIG. 3 and

FIG. 6 is a fragmentary view in side elevation showing the discharge end portion of the tube and the nozzle with the sleeve omitted.

The cylindrical body portion of the collapsible tube 8 is denoted by the numeral 10. The concavo-convex integral discharge end is denoted at 12. With reference now to FIG. 6 in particular it will be noted that the aforementioned compressibly resilient plastic nozzle is denoted by the numeral 14. This nozzle is characterized by three component parts; namely, a median cylindrical neck portion 16 which merges at its outer end 18 with a complementary slightly enlarged head 20. The inward end portion of the neck is integrated with an enlarged collar-like part which is here designated as a base 22 and which is united at 24 with the discharge end 12. The bottom of the base 22 is encircled by a shallow endless groove 26. This base is interiorly provided with a truncated conical cavity 28 (FIG. 3) which communicates with the receptacle portion 30 and which facilitates funneling the contents of the tube for discharge purposes. It should be noted (FIGS. 2 and 6) that the outstanding ledge portion of the base is provided with inclined lugs which constitute diametrically opposite cams 32. It will be further noted that the head and neck portions of the nozzle are longitudinally slotted, alternatively, bifurcated as at 34 to provide

companion jaw-like furcations one jaw to the left at 36 in FIG. 3 and a complementary jaw to the right at 38. The confronting or mating faces of these furcations are provided with grooves 40 which co-act in defining a passage, that is, passage which is communicable with the funnel 28 at one end and which opens through the convex tip 42 at the other end. This opening is provided on opposite sides with slightly raised opposed lips 44 which conjointly provide the desired openable and closable discharge mouth. It will be further noted that the passage is disposed at an oblique angle and is pitched from left to right in FIGS. 3 and 4 so that the mouth is offset and closer to one side of the marginal edge 46 to provide a convenient applicator, that is, an applicator which assists in delivering the contents of the tube to the bristles of a toothbrush with requisite nicety. It will be further noted in FIG. 6 that the peripheral surface of the head 20, that is, the surface 48 is inwardly diminished in diameter, is bevelled and thus tapered toward and merges with the outer end of the neck 16 at the junctional point 18 in FIG. 6. It follows that the nozzle 14 is unique in that it is characterized by the collar-like base 22 integral with the grooved discharge end 12, said base being at the inner end of the cylindrical neck and the neck, in turn, merging into the annular tapering surface 48 of the head 20.

This structurally and functionally unique nozzle serves to accommodate a complementary rigid plastic thimble-like sleeve 50. The sleeve is proportional in length with the overall length of the nozzle and is fittingly and aptly applied thereto as brought out in FIGS. 3 and 4 in particular. The flanged inner end portion 52 of the sleeve is slideable and rotatable on the smooth annular surface 22 of the base. In fact the terminal end portion 52 of the flange is oriented with and cooperable with the aforementioned channel or groove 26. The median portion of the bore of the sleeve is conformable with and slideable and rotatable with respect to the cylindrical surface of the sleeve 16. The outer end portion of the bore of the sleeve is flared outwardly at 58 and is cooperatively associated with the annular tapering surface 48. It will be further noted that the portion of the sleeve adjacent to the ledge of the base is provided with a shoulder 56 which is opposed to and is cooperable in a seemingly self-evident manner with the cams 32.

When the thimble-like sleeve 50 is in the forwardly projected position shown in FIG. 3 the flared surface 58 cooperates with the bevel or taper 48, compresses the component jaw-like furcations 36 and 38 and closes the mouth of the nozzle 20. Keeping in mind that the shoulder 56 is cooperable with the lug-like cams 32 it will be obvious that the sleeve 50 is rotatable and also reciprocable. When it is manually turned in the proper direction the sleeve acting on the nozzle 20 serves to close the lips 44 of the mouth. When the sleeve is turned in an opposite direction, it functions to permit the mouth to expand and open, as is brought out in FIG. 4. To facilitate turning the sleeve clockwise or counterclockwise as desired the median exterior surface portions of a sleeve are recessed, as at 60 to provide easy to use finger grips.

It is reiterated that by inclining the passageway, as brought out in FIGS. 3 and 4, the mouth at the convex tip 42 is offset to one side of the longitudinal axis of the

nozzle whereby to provide a conveniently usable applicator, that is, one which facilitates guiding and squeezing the ejected dentifrice on to the bristles of a toothbrush.

5 It is submitted that a careful study of the views of the drawings singly and collectively and an assessment of the same in conjunction with the description will enable the reader to obtain a clear and comprehensive understanding of the component parts singly and collectively and to comprehend the manner of use of this unique closure assembly. Accordingly, a more extended description is deemed to be unnecessary.

15 The foregoing is considered as illustrative only of the principles of the invention. Further, since numerous modifications and changes will readily occur to those skilled in the art, it is not desired to limit the invention to the exact construction and operation shown and described and accordingly all suitable modifications 20 and equivalents may be resorted to, falling within the scope of the invention.

What is claimed as new is as follows:

1. A dispensing container including an end wall at one end provided with an endwise outwardly projecting neck having an inner cylindrical base end supported from said end wall and an outwardly flared outer end with the inner end portions of said outer end being diametrically reduced relative to said base end, said base end, at its outer portion, defining an outwardly 25 facing annular shoulder including peripherally extending ramp surfaces, said neck base including an interior cavity opening into said container and said outer end portion of said neck having a longitudinal slot formed therein the outer end of said slot opening outwardly of the free end of said neck and the inner end of said slot opening into said cavity, the opposing portions of said neck outer end defining said slot having opposing registered longitudinal grooves formed therein opening 30 into said cavity at one set of ends and defining a discharge opening at the outer end of said neck, said grooves defining a passage extending through said neck, said neck being constructed of compressibly 35 resilient material which, when said outer end is squeezed and compressed, closes the outer end of said passage, a manually turnable sleeve rotatably mounted on said neck outer end and having inner and outer ends, said sleeve having a bore formed therethrough 40 whose outer end is flared and conforms to the outer surfaces of said outer end of said neck, said end wall having an outwardly opening groove formed therein extending about the inner end portion of said neck, the inner end of said sleeve including a counter-bore in which said inner end of said neck is received and defining 45 an annular shoulder at the inner end of said counter-bore opposing the first mentioned shoulder and having peripherally extending ramp surfaces engageable and cooperable with the first mentioned ramp surfaces to shift said sleeve axially outwardly along said neck to squeeze and compress the outer end thereof upon rotation of said sleeve in one direction on said neck, whereby to close the outer end of said passage, the inner end of said sleeve being telescoped into said 50 end wall groove when said sleeve is axially displaced 55 outwardly along said neck to close said passage and said end wall groove being sufficient in depth to allow 60 inward shifting of said sleeve from its outwardly axially 65

displaced position sufficient to allow the outer end portion of said passage to open.

2. The combination of claim 1 wherein the exterior surface portions of said sleeve are provided with indented recesses defining finger grips.

3. The combination of claim 1 wherein the outer end of said neck is convexly contoured to provide an easy-to-use dentifrice discharging applicator.

4. The combination of claim 1 wherein said passage is inclined at an angle oblique to the axis of said neck and the outer end of said passage being laterally offset relative to the neck center line to assume a location adjacent to a marginal edge of the outer end of said neck in a manner to conveniently discharge the dentifrice onto the bristles of a brush.
